UNITED STATES PATENT OFFICE

138,834

DESIGN FOR A SAFETY RAZOR

John W. Anderson, Gary, Ind.

Application July 31, 1944, Serial No. 114,658

Term of patent 14 years

(Cl. D22—3)

To all whom it may concern:

Be it known that I, John W. Anderson, a citizen of the United States, residing at 578 Broadway, Gary, in the county of Lake and State of Indiana, have invented a new, original, and ornamental Design for a Safety Razor, of which the following is a specification, reference being made to the accompanying drawing, forming part thereof.

Fig. 1 is an elevational view of a safety razor showing my new design;

Fig. 2 is a section along the lines 2—2 of Fig. 1.
Fig. 3 is a section along the lines 3—3 of Fig. 1.
The essential feature of my new design resides in the handle shown in full lines.

I claim:
The ornamental design for a safety razor, substantially as shown and described.

JOHN W. ANDERSON.
